UNITED STATES PATENT OFFICE.

EDWARD GARDNER, OF ALLEGHENY, PENNSYLVANIA.

MEAT-BLOCK.

SPECIFICATION forming part of Letters Patent No. 333,512, dated January 5, 1886.

Application filed February 26, 1885. Serial No. 157,145. (No model.)

To all whom it may concern:

Be it known that I, EDWARD GARDNER, a citizen of the United States, residing at the city of Allegheny, in the county of Allegheny 5 and State of Pennsylvania, have invented a new and useful Improvement in Meat-Blocks; and I do hereby declare the following to be a full, clear, and exact description of the same.

My invention relates to blocks for meat-chopping machines, and for general use in meat-chopping, and composed of sections arranged endwise to the face of the block; and it consists in a novel means of uniting said sections and maintaining the same in close 15 relation to one another, all as hereinafter fully described.

Heretofore it has been a common custom to use transverse sections of large tree-bodies for meat-chopping blocks; but owing to natural 20 defects found in such tree-bodies blocks cut therefrom are often imperfect in places, and when in use wear away with an uneven surface, and thus soon become useless, and in addition to the foregoing much trouble is 25 occasioned by these solid blocks splitting through their entire length. Chopping-blocks have also been made in sections, but at great cost.

The object of my invention is the production of a block which will be of equal solidity 30 throughout, and which will thus always retain and present an even chopping-surface, and, further, the production of such a block at a cost far below that of the most suitable 35 block now in use.

In the accompanying drawings, Figure 1 is a top view of a meat-block, showing my invention. Fig. 2 is a detail view in perspective of a longitudinal grooved section. Fig. 3 40 is a detail view in perspective of a key.

Similar letters of reference indicate corresponding parts.

A A designate square sections or blocks of wood of suitable length, and having their sides 45 made smooth, so that when placed side by side, as hereinafter described, a close and neat joint may be made. Throughout the entire length of the sections or blocks, and parallel with and in the four sides thereof, I cause a dovetailed 50 or other suitable-shaped groove to be cut, as shown in Fig. 2.

B B are wooden joining-keys, cut in length to correspond with sections or blocks A A, extending through the meat-block, and shaped as shown in Fig. 3, so that when the sections 55 or blocks A A are placed side by side the said keys may be closely fitted into the dovetailed space or groove in the sides of said sections or blocks, and thereby serve the purpose of maintaining and binding the same 60 together, and thus forming, by the addition of blocks A A and joining-keys B B, a chopping-block of any desired size, the whole to be bound by a light band of iron, and supported by suitable legs when used as a shop-block, 65 and when used upon a machine it may be fitted upon the device for that purpose attached to such machine. Along each side of the respective rectangular blocks is a deep undercut groove arranged opposite those in the 70 adjoining blocks, constituting between them double dovetailed channels, into which long wooden keys of corresponding size and form, are driven to draw and firmly bind the blocks together. 75

It will be readily understood that the parts which go to make up this block may be shaped upon an ordinary planing-machine, or shaped in plank-lengths and afterward cut to the desired size, and if carefully worked they may 80 be placed together and a block completed with but very little labor and in a comparatively short space of time.

Having thus described my invention, what I desire to have secured by Letters Patent is— 85

As an article of manufacture, a meat block consisting of a collection of closely-fitting rectangular blocks, each respective block being provided with a deep undercut channel or dovetail groove along each of its four sides, 90 and the blocks being joined, drawn, and firmly held together by long double dovetailed keys corresponding in size and form to the said dovetailed channels, substantially as described.

EDWARD GARDNER.
